APPARATUS FOR THE MANUFACTURE OF ICE.

APPLICATION FILED FEB. 15, 1902.

NO MODEL.

UNITED STATES PATENT OFFICE.

LOUIS BLOCK, OF MAMARONECK, NEW YORK.

APPARATUS FOR THE MANUFACTURE OF ICE.

SPECIFICATION forming part of Letters Patent No. 726,852, dated May 5, 1903.

Application filed February 15, 1902. Serial No. 94,225. (No model.)

To all whom it may concern:

Be it known that I, LOUIS BLOCK, a citizen of the United States, residing at Mamaroneck, Westchester county, in the State of New York, 5 have invented a certain new and useful Improvement in Apparatus for the Manufacture of Ice, of which the following is a specification.

The invention applies to the system of ice manufacture in which the water to be frozen is held in cans of thin metal and immersed in a tank of cold brine. The freezing commences on the surfaces and extends inward until the whole is frozen. As the ice forms 10 on the exterior, it compels the impurities in the water to aggregate in the smaller quantity of water remaining in the middle. If the operation as ordinarily conducted is arrested at the proper stage, the can may be lifted out 15 of the brine-tank, and on subsequently immersing it in a bath of tepid water to thaw it clear the ice comes out in a pure condition, with an empty space in the middle flared or trumpet-shaped at its lower end, which space 20 is not seriously objectionable; but if the lifting of the can from the brine is done too soon the cavity in the center will be unreasonably large, and if, on the other hand, it is delayed too long a still greater evil will result from 25 the whole having become solid, with a quantity of impure water frozen in, constituting what is known in the trade as a "core."

The object of my invention is to avoid the necessity for accurately timing the work. I 30 lead compressed air to the brine-tank and blow up a small stream of bubbles through the center of each can during the main portion of the freezing operation. Near the close of the freezing stops the ascent, and I cause the 35 continued accession of air to accumulate in the lower portion and force out the remaining water against a resistance which is nicely adjusted so as to be sufficient to resist the weight of the water, but will yield to the 40 force when such pressure is increased by the compressed air. By a modified form I force the air into the enveloped portion of the can and through a valve in the insulated portion 45 of the inner bottom and let it bubble up through the water until the freezing process 50 is completed.

The following is a description of what I con-

sider the best means of carrying out the invention.

The accompanying drawings form a part of 55 this specification.

Figure 1 is a section through a portion of a series of cans and associated parts in the tank of brine kept at a very low temperature by any suitable means. I have indicated 60 pipes F conveying expanded ammonia. Fig. 2 is a plan view of one of the cans. Figs. 3, 4, and 5 are on a larger scale. Fig. 3 is a central vertical section through the lower portion of a can at the commencement of the 65 freezing operation. Fig. 4 is a corresponding section showing the condition when the gradually-forming ice has closed the central passage and arrested the previously-free ascent of the air-bubbles. Fig. 5 is a corresponding section showing the same at a little 70 later stage, when the compressed air which continues to be received has accumulated above the impure water and forced it downward. Fig. 6 is a corresponding section showing 75 the condition when a can is temporarily plunged in another tank to thaw the surface and release the cake of ice. It shows how tepid water is admitted to thaw the bottom. Fig. 7 shows the can in a nearly-inverted position in the act of discharging the ice and also the tepid water. Fig. 8 is a central vertical section of a portion, on a larger scale, in the ordinary erect position. Fig. 9 is a cross-section showing a modification having a flexible 80 bottom dome-shaped. Fig. 10 shows the same with the flexible bottom domed downward. Fig. 11 shows a portion of the center of this modification on the same scale as Fig. 8. Fig. 12 is a vertical section showing still another modification. Fig. 13 is a vertical section showing still another modification. 85

Similar letters of reference indicate corresponding parts in all the figures where they appear.

A is a can of galvanized sheet-iron or other suitable material of the ordinary size and having its main portion of the standard rectangular form.

A' is the metallic portion of the bottom. 90

B is a non-conducting portion. Wood will serve well.

D is an envelop, which I will term an "air-casing," inclosing the bottom of the can A and

extending a little distance up the sides with its upper portion contracted and secured by rivets or by solder, or both. The chamber d , inclosed between this air-casing and the can, 5 forms an effectual non-conductor to retain the warmth of the water in the lower portion of the can A. It also serves to receive tepid water at a later stage to warm the bottom of the can and facilitate the removal of the ice- 10 cake.

E is a pipe leading from the air-casing D within the can and extending a little above the top thereof, which performs important functions to be described farther on. The 15 upper end of the pipe E is adapted to receive and form a tight junction with a length of hose P from a short branch pipe R', connected to a line-pipe R, which latter extends over the brine, but under the covers in the brine- 20 tank Z, and is supplied with compressed air by means of a pump Q. The pump maintains a pressure in the pipe R of four or five pounds above atmosphere. The delivery of such air through the hose P is controlled by 25 a stop-cock T, operated at will by the attendant and by which it may be cut off entirely when required. This passage is small, so that even when fully open it allows but a small escape of air. This economizes the 30 consumption of the compressed air under all possible conditions.

A metallic center piece C, preferably brass, screwed or otherwise firmly set in the wood base B, supports a removable seat C' for a 35 self-acting valve I, arranged to open upward. This seat is screwed into place and allows of easily removing the valve and seat for repairs.

M is a bent pipe inclosed in the chamber d 40 and connecting the lower end of the pipe E with the lower end of the seat C'.

Another valve V opens downward. It is held up to its seat by a coiled spring X, which abuts on the removable seat C², which latter 45 is tapped into the bottom of the passage. This is also easy to remove and repair or replace. The spring X may be adjusted by turning the nut and jam-nut V' V² to raise and lower it. The tension should be adjusted so 50 that it will hold the valve V reliably to its seat against the hydrostatic pressure of the water, but will yield and allow the valve to open and discharge water downward when that pressure is much exceeded.

55 The pipe E may extend up outside; but preferably it is within the can. Its best location is in one corner. It need not be large. Two further pipes O O' extend up from the air-chamber in other corners of the 60 can and form two small but free communications between the chamber d and the atmosphere. These should be of such caliber as to allow water to flow liberally down through one and air to escape upward through the 65 other when the whole is immersed in tepid water to liberate the ice and to allow a corresponding reverse flow of air and water at a

little later period when the whole is partially inverted to discharge the ice and empty the water from the space d . A cork O² may be 70 inserted at the top of each pipe O O' during the period while the ice is forming and removed when the can is to be immersed in the tepid-water tank Y and the tepid water is to be admitted and subsequently discharged. 75

My invention does not prevent the formation of a core-cavity, which assumes the ordinary tapered and approximately trumpet-like form, as indicated in Fig. 4. That cavity is filled with water which may contain impurities. At a late stage I expel that water automatically and supply its place with air. When my can A, nearly filled with fresh water to be frozen, stands in the brine in the tank Z and the hose P is connected to the pipe E and the cock T is opened, the stream of air delivered through the contracted aperture of the valve T flows slowly through the pipe E and the bent pipe M, lifts the valve I, and rises in small bubbles in the center of the can and 80 escapes at the top. This condition, the air exercising no influence except to gently agitate the water in the can, is continued, while the refrigerating influence of the brine acting through the thin metallic sides of the center of the can A forms a gradually-increasing 85 coating of ice around it. This coating continues below the junction of the air-casing D, because the metal of the can A conducts the caloric upward from below to the exposed portion, where it can be taken up by the brine. The part B must be so good a non-conductor 90 that the valve and adjacent parts will retain sufficient warmth to avoid the formation of ice there. The freezing action proceeds rapidly 95 in the can above the air-casing D until it completely fills with ice the upper and mid-height portions of the can. When this step is reached, 100 a new condition obtains, as follows: The air forced downward through the pipe E, no longer allowed to escape upward through the can, is arrested and by virtue of the continued flow through the contracted aperture provided by the valve T, due to the superior tension in the pipe R, increases in pressure, continuing 105 to flow up, as before, but with a higher pressure, through the valve I and to displace the water from the core-space and to fill its place with compressed air, beginning, of course, in the apex or top. The first effect of this is to 110 depress, through the valve V, the water in the can containing impurities. The delivery of the compressed air upward through the valve I and the delivery of the stained water downward through the valve V will proceed 115 continuously until the water is all expelled, after which if it shall be allowed to remain neglected and the precaution has not been taken to insert the corks O² the air will follow the water downward, moving slowly through the 120 valve V into the space d and thence upward idly, escaping through one or both of the pipes O O'; but the restraint imposed by the 125 contracted aperture in the cock T will pre-

vent any serious loss of the compressed air, even under these conditions. The impure water expelled through V will lie harmless in the bottom of the air-chamber d. It will 5 now be seen that when the freezing is completed and the can is lifted out of the brine-tank the detaching of the ice from the can is effected in the ordinary manner by immersing the can and its contents in a tank of tepid 10 water. The warmth thus applied directly to the upper and mid-height portions of the can will thaw a thin coating in the ordinary long-approved manner. Effect the almost equally rapid detaching of the ice which will form in 15 a more or less thick coating within the lower portion of the sides and near the periphery of the bottom by sinking the can with its contents sufficiently into the tepid water to allow such water to flow down through the pipe E 20 and fill the chamber d. My experiments indicate that the liberation of the ice from the metallic portion of the bottom, and if the freezing has through long delay proceeded so far as to cause the ice cake to adhere to the 25 valve or adjacent parts, the liberation from these parts also will be very nearly simultaneous with the liberation from the plane rectangular portion of the can A above. So soon as so much thawing is effected the can 30 and its contained ice are easily separated, and on the emergence of the ice cake from the can any water remaining liquid in the can will flow away. If any stained water is frozen into the lower end of the ice cake, it will be 35 in the sunk portion of the bottom below the bottom of the ice cake proper, and such objectionable ice is easily separated by a few strokes of an axe and the pure ice is ready for delivery and use. The emptying of the 40 water is effected by the same partial inverting of the can. In this position the small quantity of water which has been forced down from the can through the valve V and also the larger quantity of water received in 45 a tepid condition through the pipes O or O', mingled together in the space d, is discharged through one pipe, O, while air may enter to supply its place in the chamber d through the other pipe, O'. As soon as properly 50 drained the can may be again set upright, filled, and connected as before, and the operation may be repeated indefinitely.

Modifications may be made without departing from the principle or sacrificing the advantage of the invention. The forms and proportions of the parts may be varied within wide limits. The pipe E may be half-round and apply with the flat side against the interior of the can, or it may be round or any 55 other forms of cross-section. In any form it may, if preferred, extend up and down the exterior instead of the interior of the can. Such arrangement is shown in dotted lines in Fig. 9. Forming the valve-seats each in a 60 separate piece from the casting C, as shown in Fig. 8, facilitates the removal of a valve and its seat for examination or repairs with-

out disturbing the other parts, and I prefer such construction; but the seat and casting may be more simply made all in one, as indicated in the earlier figures. Instead of the nut V' and jam-nut V² on the upper end of the stem of the valve V, I can employ a washer and a transverse pin or any other mode of making a suitable abutment for the spring. 70 I prefer the nut and jam-nut, because they allow the force of the spring to be very conveniently and delicately adjusted by screwing down and securing the nut in any required position. In other words, it facilitates 80 adjusting the spring to the required tension—that at which the valve will stay closed reliably against the simple hydrostatic pressure of the filled can—but will open and allow the delivery of water downward as soon as the pressure from above is increased by the freezing. 85

Figs. 9 and 10 show a modification to which I attach much importance. It differs materially from the form first and mainly shown in having an annular portion of the bottom 90 of the can flexible. Such may be sufficiently thick dome-shaped rubber adapted to spring up. I can use a sheet of rubber which is naturally plane or even a sheet of other yielding material, as leather. The bent pipe shown 95 as rigid should be flexible hose when the yielding diaphragm is used. There may be no pipes O O', but simply a removable plug W in a hole in one of the sides of the casting D, with all the other parts as before described. Such is shown in Fig. 10. To operate with this form of the invention, the plug W must be removed before the can is plunged in the tepid-water bath and must be replaced when the can is to be again used to manufacture another cake of ice. Such modification 100 gives one advantage—the compressed air will not be allowed to waste at all, no matter how long the emptying and recharging of the can is postponed. As soon as the air has 105 forced down water enough to raise the pressure in the space d to two atmospheres, or whatever may be the pressure in the pipe R, the reception of air will stop. I can with the pipes O O' by only about the same amount of 110 trouble attain the same end. This is effected, as before suggested, by simply inserting corks or other plugs in the top of each pipe O and O'. In such case I keep the plug or plugs removed only while the can is immersed in the 115 tepid water and while it is afterward held partially inverted to empty. 120

A good form for many reasons is shown in Fig. 12. In this the pipe M is dispensed with, a cork O² being tightly set in each pipe O and O' and the pressure of the air received through the pipe E is felt in the whole bottom cavity d. The pressure of air thus induced lifts the valve and a succession of small bubbles rises, as before. When the arresting of 125 such rise occurs from the advanced stage of the freezing in the water above and the movement of the air stops, only a small air-space 130 is left unfilled in the bottom of the can.

It may be preferable in some cases for economy of construction or other reasons to have the bottom plane instead of depressed. Fig. 13 shows such a construction.

5 The envelop D may be of various materials, as papier-mâché made waterproof, or it may be wood. When wood is used in any part, I propose to saturate it with linseed or other oil or with paraffin to reduce the chance 10 of adhesion of the ice thereto.

Parts of the invention can be omitted entirely. I believe the valve V can be thus dispensed with, especially when the bottom is flexible, as shown in Fig. 9. When thus 15 used, the flexible portion should be so much domed that when the freezing in the main portion of the can stops the ascent of the air and the air accumulates in a compressed condition over the stained water in the core- 20 space remaining near the bottom the water can be depressed sufficiently by the simple sinking of the bottom. I prefer to use both valves, as shown. The stop-cock T affords means for varying the size of the contracted 25 aperture thereby provided; but the invention may be worked successfully with a contracted ed aperture of fixed size in its place.

I claim as my invention—

1. An ice-can A, having an exterior casing 30 D around the bottom extending upward only a portion of the height, the space between the two casings and across under the bottom constituting a chamber adapted to inclose air during the freezing period and having pipes 35 O O' to serve for the introduction of tepid water at a later period to allow its warmth to thaw the adjacent surface of the ice and rapidly release the ice cake, all substantially as herein specified.

40 2. A can A having a pipe extending up and down within it, a bottom B which is a good non-conductor of heat, and a chamber d enveloping its base, in combination with a self-acting valve I opening upward in such bottom, and provisions for leading air under pressure to such valve all arranged to serve substantially as herein specified.

3. A can A having a chamber d enveloping its base, a bottom B which is a good non-con- 50 ductor of heat, a self-acting valve I opening upward in such bottom and provisions for leading air under pressure to such valve, in combination with an air-compressor Q, pipe R, a contracted aperture T, and connection P for leading the air slowly therethrough into the can and releasing it in the bottom thereof, all substantially as herein specified.

4. A can A having a chamber d enveloping its base, a non-conducting bottom B, a self-

acting valve I opening upward in such bot- 60 tom and provisions including a pipe E within the can for leading the air under pressure to such valve, in combination with an air-com- 65 pressor Q, pipe R, a contracted aperture T restraining the flow to the can, and also with one or more additional pipes O O' arranged to serve the several functions of a vent for air and a means for admitting tepid water to the chamber d and for discharging the same, all arranged to serve substantially as herein 70 specified.

5. A can having a chamber d enveloping its base, a bottom B, a self-acting valve I open- 75 ing upward in such bottom and provisions for leading air under pressure to such valve, in combination with an air - compressor Q, pipe R, a contracted aperture T and a con- 80 nection P for leading air slowly therefrom to the can, with a pipe E for conducting air downward under pressure, and one or more 85 additional pipes arranged to serve the several functions of a vent for air and a means for admitting tepid water to the chamber d and discharging the same, a connection M in such chamber, and the additional valve V opening 90 downward, conditioned as described so that the air will accumulate in the interior of the can and force out the remaining water, adapt- 95 ed to retain the water until the freezing is far advanced and then to facilitate the discharge 100 of the impure water, all substantially as herein specified.

6. A can A having a chamber d enveloping its base, a non-conducting bottom B, a self- 105 acting valve I opening upward in such bot- 110 tom and provisions for leading air under pres- 115 sure to such valve, in combination with an air-compressor Q, pipe R, a contracted aperture T, and connections P for leading air slowly therefrom to the can, with a pipe O ar- 120 ranged to serve as a means for admitting tepid water to the chamber d and discharging the same, a connection M in such chamber, and an additional valve V and a spring X holding such valve yieldingly close, and 125 means Y for adjusting such force holding such valve to its seat, conditioned as de- 130 scribed so that the air will accumulate in the interior of the can and force out the remain- 135 ing water, all substantially as herein speci- 140 fied.

In testimony that I claim the invention above set forth I affix my signature in presence of two witnesses.

LOUIS BLOCK.
